CLAIM

The ornamental design for a storage rack for sports balls, as shown and described.

DESCRIPTION

FIG. 1 is a perspective view of a storage rack for sports balls showing my new design. The broken lines in the drawing are for illustrative purposes only and form no part of the claimed design.

FIG. 2 is a perspective view thereof.

FIG. 3 is a front elevational view thereof.

FIG. 4 is a right side elevational view, the left side elevational view being a mirror image thereof.

FIG. 5 is a rear elevational view thereof.

FIG. 6 is a top plan view thereof; and,

FIG. 7 is a bottom plan view thereof.
